UNITED STATES PATENT OFFICE.

SYLVANUS D. LOCKE, OF HOOSICK FALLS, NEW YORK, ASSIGNOR OF
ONE-HALF TO THE McCORMICK HARVESTING MACHINE COMPANY,
OF CHICAGO, ILLINOIS.

GRAIN-BINDER.

SPECIFICATION forming part of Letters Patent No. 389,581, dated September 18, 1888.

Original application filed March 29, 1881, Serial No. 29,452. Divided and this application filed April 4, 1887. Serial No. 233,546.
(No model.)

To all whom it may concern:

Be it known that I, SYLVANUS D. LOCKE, a citizen of the United States of America, residing at Hoosick Falls, in the county of Rensselaer and State of New York, have invented certain new and useful Improvements in Grain-Binders, of which the following is a specification.

This invention relates particularly to the cord holding and tying mechanism of the binder and also to its relation to the discharge-arm.

Heretofore, when the ordinary tying-bill has been used in grain-binders it has either been stopped at the end of the knotting revolution with its jaws practically transverse to the cord-slot in the breast-plate and to the line of strain of the sheaf as it is ejected by the discharge-arm, so that the knot is wrenched from the tying-jaws at a disadvantage in the ejection of the sheaf, or else, in order to completely tie the knot and yet stop the bill with its jaws pointing out in the direction of the extended slot through the breast-plate, so that the strain to slip the loop from the jaws and pull the knot ends from between them may come directly in line therewith as the sheaf is ejected, they have been given two complete revolutions; otherwise with the ordinary arrangement of knotter and holder they would fail to grasp the crossed ends of the band before the completion of the first revolution and would only reach them in or after the first quarter of the second revolution, the choice being then either to reverse them a quarter of a revolution or to carry them straight on to the completion of the second. It was found easier to do the latter. I now propose to start the tying-bill from a position of rest in which its jaws trend outward in the direction of the extended cord-slot and to give it but a single revolution to complete the knot and cause the cord-holder to concurrently carry the end strands in the opposite direction to that in which the bill is revolving so that they may meet it and anticipate the completion of its revolution and therefore enter between its jaws and be grasped a sufficient time before the revolution ends to insure the complete formation of the knot.

In carrying out this invention I employ a 50 cord stop or gate which temporarily obstructs the cord-slot that the gavel-strands may not slip past the tying-jaws before they commence their revolution, and also a discharge-arm, which in the present instance is the same as 55 the binder-arm, acting to forcibly eject the bound sheaf after the knot has been laid and the gavel strands have passed the gate, and while the knotter is in its position of rest with its jaws pointing outward along the slot; and 60 as the simplest and most effective form of holder to carry the end strands around to meet the tying-jaws in their revolution I have selected the disk-holder, mounting it upon an axis which crosses that of the knotter spindle, 65 and revolving it in such a direction that after seizing the cord-strands in the plane in which they are laid to that side of the knotter-spindle on which the binder-arm plays it carries 70 them in its revolution toward and in a sense 75 past the other side in opposition to the revolution of the said spindle, bending or wrapping them around the spindle in so doing, and causing them to meet the open knotting jaws at the completion of about the third quarter 75 of their revolution.

Certain accessory devices and details of construction will appear from the ensuing description.

In the drawings, Figure 1 is a rear elevation 80 of so much of the frame of an automatic binder embodying my invention as is necessary to an intelligent explanation thereof. Fig. 2 is a rear elevation of the band-holding and band-securing mechanism in position to receive the 85 second strand of cord from the binding-arm; Fig. 3, a perspective view of the same with the binding-arm so far advanced as to bring the spool end of the band within the range of action of the holder; Fig. 4, a like perspective 90 view of the same after the cord has been taken from the binding-arm by the holder-disks and the strands laid by the tying-bill in position to form a knot; Fig. 5, an outside detail view, partly in section, of binding-table, binding-arm, and knotter, showing the relation between the latter two while the knot is being formed; Fig. 6, a front side elevation of the

band-securing devices at the same stage of action as in the preceding figure; Fig. 7, progressive detail views showing the tying-bill in successive stages of action; Fig. 8, an elevation, from the inner side of the machine, of the knotting, holding, and cutting devices, and the gate which stops the cord, with the gear and cam wheel by which they are driven removed; Fig. 9, a view of the same from the rear, and Fig. 10 from the outer or stubble side of the machine; Fig. 11, a top plan view of the same and of the bracket in which they are mounted, the movable gate being broken away to show the crown of the tying-bill; and Fig. 12, a plan of the cord holding and cutting mechanism, partly broken away to expose the contour of the holder-plate.

A is the binding-table or receptacle supported upon the outer struts of the elevator-frame and upon a post-frame or main bracket, A', which for the purposes of this description may be like others heretofore employed by me—comprising a front post, a subtending arm, a', an overhanging arm, and feet a", sliding on rods or ways a', fast to the stubble-girt of the main frame. This table and frame and the binding mechanism borne thereby are adjusted back and forth by suitable means—for instance, a rod running longitudinally beneath it in the angle formed by its junction with the elevator and threaded into a hanger depending from its under surface.

The binder-arm B is also, for the present purposes, like others heretofore used by me—that is, it has an orbital movement imparted by a rotating crank and radius-bar, whereby it first carries the band around the gavel and subsequently acts as an ejector or discharge-arm to expel the bound sheaf. The crank b, which drives this binder-arm, is fast to a shaft, C, journaled in the overhanging arm of the main bracket and gearing by mutilated bevel-gears to stop the binder-arm during the action of the band-uniting devices with another shaft 45 running through the vertical post of said bracket, and this in turn gears with a third shaft, C', which may be termed the "tyer-shaft," journaled in the subtending arm of the bracket and driven by the gear and cam-wheel D, which operates the band-uniting mechanism, thus insuring perfect harmony in the movements of the binder.

The gear and cam wheel is provided upon one face with a short gear-segment, e, and a co-operating delay-flange, e', which serve in the present organization to drive and control the knotted or tying-bill, as will be in due time explained. Besides these I prefer to construct it with a long gear-segment, e", and a cam, e", substantially as in Letters Patent granted to me on the 14th day of December, 1880, and numbered 235,443, whereby the holding, cutting, and twisting devices therein described, or any similar mechanism, may be substituted for the knotted and its accessories shown herein.

A short post or standard, f, rises vertically from the rear end of the subtending arm of

the binder-frame in close proximity to the face of the gear and cam wheel, and to this is bolted or otherwise firmly secured the depending flange f' of a small stock or bracket, F, which overhangs said cam-wheel and supports or carries the band-securing mechanism, and may be therefore termed the "tyer-frame."

A bearing, g, depends from the tyer-frame 75 alongside the rear face of the gear and cam wheel, and in this is mounted the spindle of the knotted or tying-bill G. Another bearing, h, depends upon the other side of the gear and cam wheel to receive the spindle of a cord stop or gate, H, which prevents the strands from slipping past and escaping the knotting-jaws before they make their revolution, and the inclined stud or axle, i, of the holder I is carried in a third bearing, i', offset laterally 85 from the frame.

The knotted is a regular tying-bill, such as heretofore in general use. At the foot or lower end of the knotted-spindle is a fast pinion, k, which meshes with the short segment on the 90 face of the gear and cam wheel, so as to give the knotted a single full revolution for each revolution of the wheel, or, in other words, one revolution for each binding operation, and a delay-shoe, k', which, when the pinion passes 95 out of mesh, rides upon the delay-flange on said wheel and holds the knotted stationary in the position indicated in Fig. 2, with its jaws projecting outward and substantially parallel with the extended cord-slot in the binding-table in readiness for the next binding operation.

Immediately beneath the knotted-head, and also fast to its spindle, is a bevel-gear L, having a series of teeth, l, and a blank or delay-surface, l', and this gear meshes with and drives 105 a bevel-pinion, L', on the stud or axle of the holder, said pinion having teeth l', with which the teeth of the gear intermesh, and recesses or cut-away portions l", which slide upon the blank portion of the gear, so that the holder 110 is operated directly from the knotted, moving once during each rotation thereof, and being locked out of action, except at the proper period in said rotation.

The holder consists, in general terms, of two 115 parallel clamping-disks, M M', fast to each other and to their pinion, shaped alike, and each having two or more shoulders, m, abreast of the shoulders on the other, a curved pressing-plate, which I term the "holder-plate," 120 M', overhanging from the bracket-support and taking into the space between the disks, and a stripping-plate, M", also between the said disks, with its periphery eccentric to or spiral from their axis.

The holder-disks are described for some distance from the bases of their shoulders upon an arc concentric with their axis, and then rise eccentrically to form the succeeding shoulder. There being two shoulders, it follows that 130 there are two notches provided by this construction. The holder-plate at its point projects downward and outward into and beyond the path in which the cord is carried by the

binding-arm, so as to form, in conjunction with the disks, a converging throatway, m' , into which the arm brings the cord as it passes. Above this throatway the inner edge of the 5 holder-plate is in the main concentric with the axis of the clamping-disks, but slightly below their concentric peripheral reaches. In order, however, to check the first or old strand of cord around the gavel, belayed ever since to the previous binding operation beneath the holder from the point at which its end is clamped, so as to lie in the throatway, and wedged therein between the converging edge of the 15 holder-plate and the smooth periphery of the disks, from passing prematurely too far up said throatway and becoming entirely fast therein, or from being prematurely carried on by frictional contact in advance of the second strand just brought down when the disks are 25 started, I form at a slight distance beyond the throatway an embossment, m^2 , by which this strand will be retarded until the other is brought up against it by the positive action of the shoulders, after which both will be carried on together. Beyond this embossment, 30 at a point about diametrically opposite the throatway, there is a recession, m^3 , in the plate, the object of which is to release the old end of the cord as it is brought thereto by the disks 35 at the moment that or just after they gather the strands from the throatway into the grasp of the holder.

Located upon the holder-pinion a little in rear of the shoulders on the clamping-disks, 35 and so as to leave a little space between themselves and the face of the contiguous disk, are fingers, projections, or secondary shoulders m^4 , the object of which is to afford a support to the strands of cord stretched between the holder and the knotter, and also in some degree to assist in presenting them properly for the action of the knife by which they are severed after the knot has been tied. This knife N, having an edge, n , is pivoted to the flange 40 or offset on the supporting-bracket, and is so arranged and operated that at the proper moment it descends upon the cord in the space between one of the fingers on the pinion and one of the shoulders on the adjacent disk and 45 cuts it by a direct stroke, not by shearing against a fixed plate, thus avoiding the annoyance and clogging caused by lint in such constructions. Herein I have represented it as 50 vibrated by an arm, n' , from the rocking spindle of the gate or cord-stop, which takes 55 into a slot or aperture, n^2 , in its heel, thereby securing perfect unison in the movements of the two. After the band portion of the cord is severed, the end of the spool portion is still 60 kept securely clamped in the holder, and is thus retained until the incipient movement of the disks following the next descent of the binding-arm brings it to the recession in the holder-plate and allows it to escape. From 65 the point where it is clamped it runs behind the holder, as shown in Fig. 4, through the throatway and up to the spool. Were it al-

lowed to rest directly in contact with the lower face of the disk in the space between its end and the throatway, it would be at some 70 disadvantage, since it is intended that it shall wedge itself between the holder-plate and disks sufficiently to be held thereby, as in a secondary holder, when its extreme end is released, but at the same time to pull gradually 75 through with the revolution of the knotter, and if laid in the suggested position will not readily or certainly do so. I therefore arrange upon the offset, which supports the axle of the holder a little distance out from said throatway, a pin, p , over which the cord is laid, thus bringing it from its clamping-point and directing it into the throatway at an incline. This pin also serves to a considerable extent the 80 same office as the embossment upon the holder-plate in checking the strand from traveling through the holder in advance of its companion strand next delivered by the binder-arm.

Instead of the pin, it is obvious that a shoulder or guide may be formed upon the flange or offset to serve the same purpose.

As the clamping-disks have but two shoulders, (though the number is in a measure arbitrary,) it is evident that they will be so driven as to make one semi-revolution to each binding operation--that is, to each revolution of the knotter. This movement takes place, as above intimated, immediately after the binding arm comes down, and its effect is to carry 100 the strands from the position indicated in Fig. 3 to that in Fig. 4, the knotter acting concurrently with their passage over this space to form the loop and seize the crossed ends, and the cutter acting thereafter to sever the ends 105 thus seized.

The cord gate or stop is provided to more effectually stop the cords in position for the action of the knotter. It projects laterally from the before-mentioned rock-shaft or spindle mounted in the bearing h , and at such height and to such length as to permit it to swing somewhat above the crown of the knotter and to extend partly across the slot in the grain-table and come close to the side of the 115 binding arm when the latter descends. At the outer end it is preferably hooked, so that the cord may not slip off or past it. The gate-shaft has keyed or locked to it at its base a two-armed cross-head or block, Q, the arms q and q' of which are in different horizontal planes, and at the end of each arm is a shoe or anti-friction roll, q^2 .

Upon the front face of the gear and cam wheel is a cam-track, along which the roller of the arm q travels as the wheel revolves. While the binding arm is up and moving inward to gather the gavel, and for an interval after its descent, the roller travels on the raised portion R of the track, and the gate is held cut 125 across the slot in the grain-table, which, it will be understood, herein represents any plate or shield interposed between the gavel and the tying-head; but when the knotter has com-

pleted or about completed the first half of its revolution the roller descends upon a lower portion, r , of the track, and the roller upon the arm q' , which is the rear roller, 5 and hitherto has traveled upon the plane face of the wheel, rides up a slight lug or incline, r' , and thus positively rocks the shaft, causing the gate to give away before the cord sufficiently to render up a little slack 10 to the knotter. The forward roller continues along the depressed trackway until the knotter has finished its revolution, securely 15 grasped the ends of the cord between its jaws, and come to a full stop, when it reaches and descends to a still lower trackway, r^2 , the rear roller at the same moment surmounting another and more prominent lug, r^2 , whereby 20 the gate is thrown fully open out of the way of the band cord to permit the binding-arm, which now starts from its station of rest, to 25 pull the loop from the knotter and eject the bound sheaf from the machine, the cutter operated in this final movement of the gate having already severed the cord from the holder. 30 In binders generally the cord in its passage from the spool to the holder runs through an eye in the binding arm and is never disconnected therefrom. Such an arrangement may be adopted in my machine; but the arm 35 shown herewith is adapted to engage with the cord only when carrying it about the gavel and to release or deliver it entirely up to the holder after the gavel is encircled, so that when the binding operation is completed and the sheaf ejected the cord from which the next band is to be taken is left stretched directly from the newly-clamped end through 40 the throatway of the holder to the slack take-up or other overhead guide, and thence to its source of supply.

The binding arm has, therefore, on the side facing the knotting, holding, and cutting devices, flanges or shoulders s , s' , s^2 , laid transversely to its body, but at an inclination to take them readily through the grain. The flange s , when the arm is down and at rest, comes just above the path of the knotting-jaws and the flange s' just below, while the flange s^2 comes beneath the throatway of the holder. 50 The jaws in their revolution enter the upper end of the recesses thus formed and gather the strands of cord from the gavel which have been stopped by the gate at such a point that they are in contact with the crest of the flanges s and s' , and are thus raised out in position to be caught fairly against the inner curved side of said jaws. The point of the holder-plate projects sufficiently to enter the lower recess, thus making practically a closed 55 connection between the binding-arm and the throatway, and the shoulders of the holder-disks also extend into said recess in their rotation to seize the cord.

The flange s^2 is slightly hollowed or rounded 60 out beneath, so that as the binding-arm in its inward movement to gather a gavel comes against the cord leading from the ball or

spool to the knotter it may take over it and carry it, as indicated in Figs. 1 and 2, down around the gavel, against the gate or cord-stop, and to the holder, bringing the upper strand of the bight or bend thus formed, and which is pushed out by the overlying flange s' , as above explained, inside the point of the holder-plate and into the entrance of the 75 throatway.

The knotter now starting to form the loop, the movement of the holder immediately follows, and the nearest set of shoulders of the holder-disks are brought against the newly-delivered strand, carry it up the throatway alongside the strand previously lying therein and already released as to its extreme end by the incipient action of the holder, and, being pulled through said throatway by the rotation 85 of the knotter, push the two before them away from the slot in the binding-table or deck and in a direction opposed to the revolution of the holder-spindle, bending or wrapping them around said spindle until they reach the position shown in Fig. 4, where they meet and enter between the open jaws of the tying-bill at about the third quarter of its revolution, and then are brought to a stop. In this movement the lateral pull upon the cord causes the lower strand 95 of the bight or that strand now running to the spool to spring out from beneath the flange s^2 , catch over the pin p , and enter the throatway behind the shoulders that are carrying the gavel-strands, where it remains until the next 100 binding operation. When the knotter has completed its revolution to form the knot and has come to a rest with the end strands grasped between its outwardly-pointing jaws, and these end strands have been severed from 105 the holder by the action of the knife, and the cord-gate has been thrown open to leave the slot unobstructed, the binding-arm starts to pull the band therefrom and eject the bound sheaf, which it does by a direct outward movement, pulling the band from the jaws in the direction in which they are pointing. It is 110 desirable, though not essential, that at this moment the loop should be pushed off of the surface of the jaws and run down upon the end 115 strands instead of being drawn off by the pull of the band, since under the first condition it will be closed upon the end strands before the stress comes upon them to withdraw them from the knotter, and will therefore be tightened 120 by this stress, while under the second it will tend to bind about the jaws, and undue force 125 will be required to move it. Hence I mount upon the binding-arm a stripper-finger, t , which, as the arm moves outward, sweeps the crest of the knotter from heel to point and pushes the loop before it. That this finger may not interfere with the passage of the arm through the stream of grain at the time the gavel is divided off, I arrange it to play longitudinally through the arm and attach it at 130 its rear end to the upper free end of a spring, t' , fast to the side of the arm. This spring is so limited in its outward play and has such

strength as to hold the stripping-finger with its point flush with the forward side of the binding-arm or with the crest of the flange ⁸, through which it plays while the arm is passing through grain; but as the arm moves along the slot in the grain-table the spring comes against the vertical flange of the cap-plate S, which for this purpose is rounded or beveled at its inner end and stands out into the slot, and is pressed against the side of the arm, so as to cause the stripper to project on the outer side under the cap and behind the knotter. After the stripper has swept the knotter, the flange drops away suddenly, so that it may be again withdrawn by the spring before the binding arm rises. The stripper serves also another purpose, for as it is caused to project before the arm comes to a stop, it will form an abutment, against which the inner side strand of the cord about the gavel may rest, and by which it will with certainty be pushed or brought up to the gate above the knotter and alongside the outer strand, and thereafter, while the knotter revolves, the two strands will be held against undue lateral displacement within a sort of closed eye formed by the side of the binding-arm, the cord-gate, stripper, and the edge of the overhead cap.

In order that the cord-gate may hold the cord back upon the knotter and positively prevent the loop from slipping off or escaping before its time, it is preferably brought so low that it nearly touches the crown of the knotter and actually intercepts the path of the stripper. It is evident, therefore, that in the final opening movement of the gate it will be thrown far enough back to allow the point of the stripper to clear it when the binding-arm passes.

The specific or individual constructions of the knotter, holder, and cord-gate, and certain limited combinations into which one or more of them enter among themselves, depending upon features of such individual construction, have been made the subject of an application filed by me on the 29th day of March, 1881, Serial No. 29,452, and of which this is a division. The combinations herein-after claimed depend rather upon the relative arrangement and mode of operation of these parts considered as types than upon any such individual features of construction, and therefore while I have refrained from claiming these combinations in the parent case, either generically or specifically, it is not my intention herein to limit myself to the specific devices employed unless otherwise in any claim explicitly stated.

I claim—

1. The combination, substantially as herein-before set forth, with a knotter driven in one direction only and stopped with its jaws trending outwardly as soon as the crossed ends of the band are seized, of a shield or decking separating it from the grain-passage and having a cord-slot that extends past the knotter and permits the cord-strands to be

carried therewith while still in the grasp of the holder, and a discharge-arm which acts while the knotter is at rest in this outwardly trending position. 70

2. The combination, substantially as herein-before set forth, with a knotter driven in one direction only and stopped with its jaws trending outwardly as soon as the crossed ends 75 of the band have been seized, of a holder receiving both ends from the binder-arm, and mechanism which actuates it to carry said ends across the knotter-spindle in opposition to its revolution, that they may anticipate the coming around of the tying-jaws. 80

3. The combination, substantially as herein-before set forth, of a tying-bill, mechanism which gives said tying-bill a single revolution and stops it with its jaws trending outward in the 85 direction of the extended slot in the covering-shield, a holder receiving the cord-strands at one side of the knotter-spindle, and mechanism actuating said holder to carry said strands toward the other side of the spindle in opposition to the direction in which said spindle revolves in order to meet the open tying-jaws before they end their revolution. 90

4. The combination, substantially as herein-before set forth, of a tying-bill, mechanism 95 which gives said bill a single revolution and stops it with its jaws trending outward in the direction of the extended slot in the covering-shield, a cord-stop temporarily obstructing the slot inside of said bill to prevent the escape of the strands past the tying-jaws until they begin to revolve, a cord-holder at the outer side of the bill receiving the cord-strands at one side of the knotter-spindle, and mechanism actuating said cord-holder to carry said 100 strands toward the other side of the spindle in opposition to the direction in which said spindle revolves. 105

5. The combination, substantially as herein-before set forth, of a tying-bill, mechanism 110 which gives said bill a single revolution and stops it with its jaws trending outward in the direction of the extended slot through the covering-shield, a rotary cord-holder arranged on the outer side of said tying-bill and at the 115 same side of the cord-slot, and mechanism actuating the holder-disk to carry the cord-strands away from the cord-slot and across the knotter-spindle in opposition to the direction in which the tying-bill revolves to anticipate the 120 coming around of its jaws. 120

6. The combination, substantially as herein-before set forth, of a tying-bill, mechanism which gives said bill a single revolution and stops it with its jaws trending outward in the 125 direction of the extended slot through the covering-shield, a cord-stop temporarily obstructing the slot inside of said bill to prevent the escape of the strands past the tying-jaws until they begin to revolve, a rotary cord-holder arranged on the outer side of said tying-bill and at the same side of the cord-slot, and mechanism actuating the holder-disk to carry the cord-strands away from the cord-slot and 130

across the knotter-spindle in opposition to the direction in which the tying-bill revolves to anticipate the coming around of its jaws.

7. The combination of a tying-bill, mechanism which gives said bill a single revolution and stops it with its jaws trending outward in the direction of the extended slot through the covering-shield, a rotary cord-holder arranged on the outer side of said tying-bill in a plane 10 transverse to the cord-slot, but slightly inclined to the knotter-spindle, and mechanism actuating the holder-disk to carry the cord-strands away from the cord-slot and across the knotter-spindle in opposition to the direction in 15 which the tying-bill revolves.

8. The combination, substantially as hereinbefore set forth, of a tying-bill, mechanism which gives said bill a single revolution and stops it with its jaws trending outward in the 20 direction of the extended slot through the covering-shield, a rotary cord-holder arranged on the outer side of said tying-bill and at the same side of the cord-slot, mechanism actuating the holder-disk to carry the cord-strands away 25 from the cord-slot and across the knotter-spindle in opposition to the direction in which the tying-bill revolves, and a discharge-arm ejecting the bound sheaf sidewise, whereby the knot is pulled from the tying-jaws by a direct 30 strain in the direction of their length.

9. The combination, substantially as hereinbefore set forth, of a tying-bill, mechanism which gives said bill a single revolution and stops it with its jaws trending outward in the 35 direction of the extended slot through the covering-shield, a cord-stop obstructing the cord-slot on the inner side of said tying-bill, a cord-holder on the outer side thereof, mechanism actuating said cord-holder to carry the cord- 40 strands away from the cord-slot and across the knotter-spindle in opposition to the direction in which it revolves, and a discharge-arm which

ejects the bound sheaf sidewise after the band ends have been severed and the tying-bill stopped, whereby the knot is pulled therefrom by a direct strain in the direction in which the jaws trend. 45

10. In an automatic grain-binder, the combination of a revolving tying-bill, a revolving cord-holder in a plane inclined to the axis of 50 the tying-bill, and an intermeshing bevel-pinion upon the shaft or spindle of the cord-holder, whereby the latter is controlled by the revolution of the former.

11. The combination of the revolving knotter or tying-bill, the revolving cord-holder, the delay-gear upon the shaft of the knotter, 55 and the intermeshing delay-gear upon the shaft or spindle of the holder.

12. The combination of the knotter, the 60 holder driven thereby, the cord-gate, and the single gear and cam wheel driving both knotter and gate.

13. The combination of the knotter, the holder driven thereby, the cord-gate, the cutter actuated by the movement of said gate, and 65 single gear and cam wheel driving both knotter and gate.

14. The combination of the binding-arm, its lateral flanges, the tying-bill, and the cord-holder with its point entering between two of 70 said flanges, substantially as described.

15. The combination of the binding-arm, its lateral flanges, the stripper which it carries, the gate, and the tying-bill, substantially as 75 described.

16. The combination of the knotter, the vibrating cord-gate, and the single gear and cam wheel by which they are driven, whereby their movements are timed in unison.

SYLVANUS D. LOCKE.
